UNITED STATES PATENT OFFICE.

FRANK J. BOBSEINE, OF GOWANDA, NEW YORK.

GUTTER-CLEANING DEVICE FOR STABLES.

Application filed April 26, 1920. Serial No. 376,726.

To all whom it may concern:

Be it known that I, FRANK J. BOBSEINE, a citizen of the United States, residing at Gowanda, in the county of Cattaraugus, 5 and State of New York, have invented certain new and useful Improvements in Gutter-Cleaning Devices for Stables, of which the following is a specification.

This invention relates to gutter cleaning devices for stables and has as its object generally to provide means whereby a stable gutter may be cleaned mechanically thus obviating the expenditure of manual labor in performing this task.

Another object of the invention is to provide, in a device for the purpose stated, embodying a conveyor flight movable longitudinally in the stable gutter, novel means whereby the movement of this conveyor flight may be readily controlled both in its movement in the direction to clean the gutter and in its return movement, novel means being provided for maintaining the flight in taut condition during the operation of the device and for regulating the speed of travel of the same particularly as it is being returned to position within the gutter.

Various other objects which I have in view and various advantages for the different mechanisms employed will be made clear in the specific description of the structure which is to follow.

In the accompanying drawings:

Figure 1 is a view in side elevation of the device embodying the present invention installed in operative relation to a stable gutter, parts being shown in section and parts being broken away;

Fig. 2 is a top plan view of the structure shown in Fig. 1;

Fig. 3 is a perspective view illustrating a portion of the mechanism removed from the frame by which it is supported;

Fig. 4 is a perspective view of one of the control levers;

Fig. 5 is a vertical longitudinal sectional view through a portion of the structure shown in Fig. 4;

Fig. 6 is a view partly in side elevation and partly in section illustrating one of the sprockets employed;

Fig. 7 is a horizontal sectional view illustrating a portion of the mechanism;

Fig. 8 is a view similar to Fig. 2 illus-

trating a modified form of the invention;

Fig. 9 is a side elevation of a brake which is employed in connection with the winding or take up drum for the conveyor flight.

In the drawings the numeral 1 indicates in general the interior of a barn or stable and the numeral 2 indicates a gutter which extends within the barn or stable and outwardly at one end through an opening 3 in one wall of the stable, this gutter being designed to extend above the frame within which are mounted the various mechanisms of the present invention. The conveyor flight heretofore referred to comprises spaced sprocket chains 4 and transverse slats or bars 5 which may be of angle iron or of any other suitable material and of any desired construction. This conveyor flight is of dimensions to travel freely within the gutter 2 and yet is so proportioned and constructed that in its movement within the gutter in the direction of the opening 3, it will serve effectually to clean the gutter. Means which will presently be described, is provided for imparting motion to the conveyor flight in the direction stated, and means is likewise provided for imparting motion in an opposite direction to the conveyor flight so as to return the same to normal position within the gutter 2, this latter means including a cable 6 which is connected as indicated at 7 with the inner end of the conveyor flight and is passed upwardly about a pulley 8 located at that end of the gutter opposite the end which extends through the opening 3. From the pulley 8, the cable 6 is led upwardly and thence over other pulleys 9 arranged overhead, the cable being finally led downwardly and about a pulley 10 and through an opening 11 formed in the wall of the stable above the opening 3.

The several mechanisms embodying the invention are mounted within or upon a suitable framework which is indicated in general by the numeral 12 and which is mounted exteriorly of the stable or barn. This framework comprises a top 13 which is rectangular and preferably formed from one piece of angle iron cut and bent to the required shape. This top 13 is supported by legs or uprights 14 and is suitably braced as indicated by the numeral 15. The frame structure also includes side rails 16 secured to the legs or uprights 14 and projecting at

their rear ends beyond the remainder of the frame structure to provide abutment arms 17 designed to engage against the adjacent wall of the barn or stable as clearly shown in Figs. 1 and 2 of the drawings so as to brace the frame structure with relation to the said wall and likewise prevent the winding or take-up drum for the conveyor flight from coming in contact with the wall of the stable or barn as will presently be made apparent.

As before stated, the conveyor flight travels within the gutter 2 in the operation of the device and the gutter at one end extends through the opening 3 and above the top 13 of the frame structure 12, being preferably secured to this structure in any suitable manner. The chains 4 of the flight, after passing the said end of the gutter, are trained about sprocket gears 18 which are fixed in any suitable manner upon a shaft 19 rotatably mounted in suitable bearings in or upon the side members of the top 12 of the frame structure. To prevent accidental jumping of the chains from the sprocket gears 18, each gear is preferably provided with a circular guard head 20 located at its outer face and of greater diameter than the said gear, the opposing faces of the two heads being preferably convex as illustrated in Fig. 7 of the drawings so as not to offer any frictional resistance to the passage of the chains 4 about the gears 18. After passing about the sprocket gears 18, the chains 4 are led rearwardly within the frame structure 12 and are suitably secured as at 21 at their adjacent ends to the winding or take-up drum heretofore referred to and which is indicated in general by the numeral 22. This drum is suitably fixed upon a shaft 23 mounted in suitable bearings in the sides of the frame structure, as for example in the side bars 16, the heads of the drum, indicated by the numeral 24, being of a diameter such that their peripheries will be spaced from the wall of the barn or stable when the abutment arms 17 are in engagement against the said wall as shown in Figs. 1 and 2. Between the sprocket gears 18 and the drum 22, the stretches of the chains 4 may be passed over suitable idle rolls or pulleys 25 which serve to suitably tension the said chains.

Power is supplied to the shaft 19 by means which will now be described. A drive belt 26 leads from any suitable source of power such for example as an internal combustion engine and is trained over a pulley 27 fixed upon one end of a shaft 28 which is rotatably mounted in suitable bearings in the top member 13 of the frame structure 12 inwardly of the shaft 19 and parallel thereto. A crown gear 29 is fixed upon the shaft 28 and has inner and outer concentric series of teeth, the inner series being indicated by the numeral 30 and the outer series by the

numeral 31. A sleeve 32 is loosely mounted upon the shaft 28 beside the inner face of the crown gear 29 and is provided with a stepped bearing 32' having a ball race 33, this bearing receiving the inner end of a shaft 34 which carries a pinion 35. The pinion 35 is mounted for sliding movement upon the said shaft 34 but is rotatable with the shaft and consequently the pinion may be slid into position meshing with the gear teeth 30 or with the gear teeth 31 or to occupy an intermediate or neutral position if desired. In order that the pinion 35 may be shifted in the manner stated there is provided in connection therewith a yoke 36 of the usual type the movement of which is effected by a hand lever 37, this lever being fixed upon one end of a rod 38 mounted for rocking movement transversely upon the top member 13 of the frame structure 12. The lever 37 is held in its positions of adjustment by the cooperation of a hand pawl device 39 carried thereby, with a segmental rack 40 fixed upon the said member of the frame. The opposite end of the rod 38 has secured upon it an upstanding arm 41 to which is connected one end of a rod 42 the forward end of which rod is connected with the said yoke 36 so that when the lever 37 is manipulated, the pinion 35 will, as stated, be shifted so as to mesh either with the teeth 30 or the teeth 31 or to occupy a position between these series of teeth and out of mesh with the teeth of both series. The shaft 34 is rotatably mounted near its forward end in a bearing block 43 which block is in turn guided for vertical movement in a suitable bracket 44 fixed upon the top of the frame structure, a spring 45 being provided beneath the block for yieldably resisting downward movement thereof. A worm 46 is fixed upon the forward end of the shaft 34 and this worm is designed to mesh with a worm pinion 47 fixed upon the shaft 19. The numerals 48 and 49 indicate toggle links which are pivotally connected with each other as at 50, the link 48 being pivotally connected at its lower end as at 51 to the bearing block 43, and the link 49 being pivotally connected at its upper end as at 52 to a suitable bracket 53 upon the frame structure. The pivot 52 is a fixed one and when the toggle links 48 and 49 are in the position shown in Fig. 3 of the drawings they have been thrown slightly past dead center, their further movement in this direction being prevented, however, by a stop lug 54 upon the link 49 which lug engages one edge of the link 48. In this position of the links the worm 46 is maintained in mesh with the worm pinion 47, but by breaking the toggle, the shaft 34 may be swung upwardly so as to move the worm out of mesh with the worm pinion. In order that this may be done a rod 55 is pivotally connected with the toggle 49.

link 49 and is led rearwardly and secured to the forward end of a sleeve 56 which is formed in one side with a longitudinally extending slot 57. A spring 58 is arranged 5 within the sleeve and bears at its forward end against the closed forward end of the sleeve and at its rear end against the enlarged end 59 of a finger 60 which projects laterally from the end of an arm 61 secured 10 upon a shaft 62 mounted for rocking movement within suitable bearings upon the top member 13 of the frame structure. An operating lever 63 is fixed upon the other end of this shaft and is provided with a hand 15 pawl device 64 for cooperation with a segmental rack 65 whereby the lever may be held in positions of adjustment. It will now be evident that the lever 63 may be manipulated so as to spread the toggle or break the 20 same and thus lower or elevate the bearing block 43 for the shaft 34 so as to bring the worm 46 into or out of mesh with the worm pinion 47. When the lever 63 is so manipulated as to break the toggle joint, the 25 spring 45 will tend to throw the bearing 43 in an upward direction thus causing the worm 46 to clear the worm pinion 47 and when the lever is manipulated so as to shove forwardly upon the rod 55, the toggle links 30 will be spread until they assume about the relative positions shown in Fig. 3 of the drawings whereupon they will lock and thus hold the shaft 34 in a lowered position and with the worm 46 in mesh with the worm 35 pinion 47. By the employment of the springs 45 and 58, the parts are relieved of shock when the hand lever 63 is manipulated. It will now be evident that the application of power to the shaft 19 from the 40 shaft 28 may be readily controlled. It will also be evident that when the shaft 19 is rotated in one direction the conveyor flight will be caused to travel longitudinally in the gutter 2 so as to clean the said gutter and 45 when the device is operated in this manner, means which will now be described, operates simultaneously to take up or wind the conveyor flight after it passes over the sprocket gears 18.

50 In order to transmit power to the winding drum 22 for the purpose of taking up or winding the conveyor flight as above mentioned a sprocket gear 66 is loosely mounted upon the shaft 19 and has trained over it a 55 sprocket chain 67 which passes also over a sprocket gear 68 fixed upon the shaft 22. A clutch disk 69 is fixed upon the shaft 19, and clutch arms 70 are pivotally mounted as at 71 upon the gear 66 and have shoes 72 for frictional engagement with the periphery of the disk 69. Turnbuckle links 73 are pivotally connected to the ends of the arms 70 and to a collar 74 which is loosely 60 slidably mounted upon the shaft 19. An arm 75 is pivotally connected at one end as at 76 to a bracket 77 upon the frame structure and engages the collar 74 in a manner to provide for sliding movement of the collar upon the shaft 19 when the arm is rocked. A rod 78 is swiveled as at 79 to a 70 fixed part of the frame structure and extends at its outer end portion through an opening 80 in the outer end of the arm 75. This portion of the rod is threaded as indicated by the numeral 81 and a hand wheel 82 is 75 threaded upon the said portion of the rod and may be rotated so as to be adjusted longitudinally of the rod. A spring 83 is disposed upon the rod 78 and bears between the hand wheel 82 and the outer end of the arm 80 75. It will now be evident that when the hand wheel 82 is rotated in one direction, the arms 75 will be swung inwardly thereby spreading the outer ends of the arms 70 and causing the shoes 72 to frictionally clutch 85 the periphery of the clutch disk 69 thus connecting the sprocket gear 66 for rotation with the shaft 19 although there may be a slippage of the parts when the occasion arises. In this manner rotary motion is 90 transmitted to the shaft 23 from the shaft 19 so that the conveyor flight will be taken up by and wound upon the drum 22. Of course, as a greater length of the conveyor flight is wound onto the drum, there will be 95 a tendency for the flight to be taken up the more rapidly but under these conditions the shoes 72 may slip over the periphery of the clutch disk 69 so as not to impose any undue stress upon the chains of the conveyor flight. 100 When the conveyor flight is to be unwound from the drum in the return movement of the said flight to its normal position within the gutter the hand wheel 82 may be rotated in the direction the opposite of that 105 above stated so as to release the shoes 72 from frictional engagement with the periphery of the clutch disk 69 and consequently no rotary motion will be imparted to the shaft 23 through the medium of the sprocket 110 chain 67 as the gear 66 will not under these conditions be rotated by the shaft 19. It is desirable at this time that the reverse rotation of the drum 22 be somewhat retarded so that the conveyor flight cannot unwind too 115 rapidly from the said drum and become entangled or otherwise interfere with the return of the flight to its normal position. For this purpose there is provided in connection with the drum a suitable brake device which 120 is clearly illustrated in Figs. 3 and 9 of the drawings and which will now be described. A brake drum 84 is associated with the sprocket gear 68 or it may be separate from the said gear and secured upon the shaft 23. 125 and within this drum are arranged brake shoes 85 which are supported at the opposite ends of a transverse head 86 loosely mounted upon the shaft by means of a hub 87. These shoes include studs 88 which pro- 130

ject through slots 89 in the said transverse head, and links 90 are pivotally connected at their lower ends with these links and at their upper ends as at 91 to the lower end 5 of a rod 92 in turn pivotally connected at its upper end to an operating lever 93 which may be manipulated for the purpose of raising or lowering the rod 92 and thus drawing together or moving apart the brake shoes 10 so as to bring the same out of braking contact with the surface of the drum 84.

The unwinding of the conveyor flight from the drum 22 is, of course, occasioned by winding up of the cable 6 which is connected with the said flight and in order that this may be accomplished, the cable is connected with a winding drum 94 mounted upon a shaft 95, and one head of which drum is in the form of an internal gear 96. The shaft 95 is counter to the shaft 28, and a pinion 97 is held for rotation upon the shaft 28 and is slideable thereon into and out of mesh with the internal gear 96. In order that the pinion 97 may be so shifted, a yoke 25 98 is associated therewith and is actuated through a hand lever 99 held in positions of adjustment by means of a hand pawl device 100 which coacts with a rack 101 upon the frame of the device. It will now be evident 30 that when it is desired to take up the cable 6 so as to unwind the conveyor flight from the drum 22 and return the said flight to its normal position within the gutter, the lever 63 may be manipulated so as to effect 35 upward swinging movement of the shaft 34 or the pinion 35 may be shifted to neutral position and then, the lever 99 is to be operated so as to bring the pinion 97 into mesh with the gear 96 whereupon the drum 97 40 will be rotated to wind up the cable 6, the hand wheel 82 having previously been manipulated so as to release the clutch comprising the shoes 72 and disk 69.

At this point it may be stated that it is 45 preferable that the teeth of the sprocket gears 18 be formed as shown in Fig. 6 of the drawings, each tooth having a relatively straight pulling side indicated by the numeral 102 and a rounded rear side 103. By 50 thus shaping the teeth, the rear sides thereof will sweep or wipe past the links of the sprocket chains 4 as these chains are passing more or less rapidly back to normal position within the gutter. In this manner the 55 teeth of the sprockets 18 will not drag the upper stretches of the chains downwardly past the end of the extension of the gutter as would otherwise be liable to occur.

The conveyor flight heretofore described 60 is designed to discharge onto an elevator which in that form of the invention shown in Figs. 1 to 7 inclusive travels in the same general direction as the conveyor flight and in that form of the invention shown in Fig. 65 8, travels at right angles to the path of

travel of the conveyor flight, the elevator in either instance being designed to discharge at a point relatively remote from the discharge end of the conveyor and onto a heap 70 or pile or into a wagon or other conveyance.

In the first mentioned form of the invention, the elevator is indicated in general by the numeral 104 and the same comprises an endless chain or belt conveyor 105 which is mounted within a suitable frame 106 75 mounted at its lower end to swing about a shaft 107 journaled in suitable bearings 108 upon the side members 16 of the frame structure 12. A cable 109 is connected with the upper or outer end of the conveyor 80 frame 106 and is wound about a drum 110 rotatably mounted upon the forward end of the said frame structure 12. A crank handle 111 is fixed onto one end of the supporting shaft for this drum and the shaft 85 likewise carries a ratchet 112 with which coacts a pivoted pawl 113 for the purpose of preventing backward rotation of the shaft. In this manner the conveyor or elevator may be swung upwardly or permitted to lower so 90 as to suitably elevate its discharge or outer end. In order that the conveyor 105 may be driven, a sprocket gear 114 is loosely mounted upon the shaft 19 and a chain 115 is trained about this gear and about a similar gear 116 upon the shaft 107, the chain being held suitably taut by means of a tightener 117 of any approved type. It is desirable 95 that the conveyor 105 be driven only while the conveyor flight which operates within the gutter is traveling in a manner to clean the gutter and to discharge onto the said conveyor 105, and that the said conveyor 105 remain idle while the conveyor flight 4 is being returned to its normal position 100 within the gutter, and in order that this may be accomplished, a collar 118 is fixed upon the shaft 19 and carries pawls 119 which are designed to engage with ratchet 110 teeth 120 formed within the face of the gear 114, the teeth clutching the gear with the shaft when the shaft is rotated in a forward direction and riding freely past the ratchet teeth of the gear when the shaft is 115 rotating in a backward direction.

In that form of the invention shown in Fig. 8 of the drawings, the elevator comprising the said conveyor 105 is positioned at right angles with relation to the discharge end of the gutter and is suitably mounted at its lower end for swinging movement about a shaft 121 which is mounted in suitable bearings upon one of the side members 16 of the frame structure. This shaft is provided at one end with a beveled pinion 122 which meshes with a bevel gear 123 fixed upon the shaft 107 heretofore described.

It will be understood, of course, that the frame structure of the machine as well as 130

other parts thereof may be anchored in any desired manner and that so much of the gearing as occasion may require, may be enclosed and supplied by any suitable means with oil.

A turnbuckle 42' is preferably interposed in the length of the rod 42 so that the rod may be adjusted as to length when required to take up wear.

10 Any suitable means may be provided to prevent the yoke 36 from turning with the pinion 35 in the rotation of the latter.

A collar 43' is secured upon the shaft 34 to prevent the shaft slipping out of the 15 sleeve 32.

20 Springs 90' are arranged upon the links 90, and the links are slotted at their points of connection with the pivot 91 so that the movement of the parts will be cushioned and so that the shoes 85 will be assisted in 25 performing their gripping function.

It will be understood that any suitable tensioning means may be provided in connection with the chain 67.

25 In the first described form of the invention the elevator is driven from the shaft 107 by a sprocket chain 107' tensioned as at 107'; and, in the form of the invention shown in Fig. 8, the elevator is driven from 30 the shaft 121 by a sprocket chain 121' which may be similarly tensioned.

A small grooved pulley 19' is fixed upon the shaft 19 so that the cable 6 may be guided over the shaft in the event the apron 35 is drawn out over the sprockets 18.

Having thus described the invention, what is claimed as new is:

1. In a device of the class described, a 40 conveyor flight, take-up means to which the front end of the flight is connected, a flexible pull element connected with the rear end of the flight, a take-up means for the said pull element located in advance of the front end of the conveyer flight, a driving means, and means for selectively connecting the driving means with either take-up means.

2. In a device of the class described, a conveyor flight, take-up means to which one end of the flight is connected, a power shaft, 50 a shaft driven therefrom, normally idle gearing between the last mentioned shaft and the said take-up means, means for rendering the gearing active, a flexible pull element connected with the other end of the flight, and a take-up means for the said pull element operable from the power shaft.

3. In a device of the class described, a conveyor flight, take-up means to which one end of the flight is connected and arranged in 60 its operation to effect travel of the flight in one direction, means for effecting travel of the flight in the opposite direction, a power shaft, means for operatively connecting the last mentioned means with the power shaft, 65 a shaft counter to the power shaft, means

operable to establish driving connection between the power shaft and the shaft counter thereto, and means for transmitting power from the counter shaft to the said take-up means.

4. In a device of the class described, a conveyor flight, take-up means to which one end of the flight is connected, a power shaft, a shaft counter thereto, gear means operable from the counter shaft to operate the take-up means, a gear upon the counter shaft, a transmission shaft mounted for swinging movement about the power shaft as a center, a gear upon the power shaft, a gear upon the swinging transmission shaft for mesh with 80 the gear upon the power shaft, a gear upon the transmission shaft to mesh with the gear on the counter shaft, and means for swinging the said swinging shaft into and out of position to effect meshing of the last mentioned gears.

5. In a device of the class described, a conveyor flight, take-up means to which one end of the flight is connected, a power shaft, a shaft counter thereto, gear means 90 operable from the counter shaft to operate the take-up means, a gear upon the counter shaft, a transmission shaft mounted for swinging movement about the power shaft as a center and actuated therefrom, a gear 95 upon the transmission shaft to mesh with the gear upon the counter shaft, means for swinging the said transmission shaft into and out of position to effect meshing of the last mentioned gears, and means for locking 100 the transmission shaft in driving position.

6. In a device of the class described, a conveyor flight, take-up means to which one end of the flight is connected, a power shaft, a shaft counter thereto, gear means operable from the counter shaft to operate the take-up means, a transmission shaft mounted for swinging movement about the power shaft as a center and operated therefrom, a gear upon the counter shaft, a gear upon the transmission shaft to mesh with the gear upon the counter shaft, means for swinging the said transmission shaft into and out of position to effect meshing of the last mentioned gears, a bearing for the free end of 115 the transmission shaft, a toggle link connected with the bearing, a toggle link connected with the first mentioned link, and manually operable means connected with one of said links for spreading and breaking 120 the toggle.

7. In a device of the class described, take-up means, a conveyer flight having one end connected to said take-up means, a power shaft, a shaft counter thereto, gear means 125 operable from the counter shaft to operate the take-up means, a gear upon the counter shaft, a transmission shaft mounted for swinging movement about the power shaft as a center and actuated therefrom, a gear 130

upon the transmission shaft to mesh with the gear upon the counter shaft, means for swinging the said transmission shaft into and out of position to effect meshing of the 5 last mentioned gears, a bearing for the free end of the transmission shaft, a toggle link connected with the bearing, a toggle link connected with the first mentioned link, manually operable means connected with one 10 of said links for spreading and breaking the toggle, and means cushioning the movement of the said bearing.

8. In a device of the class described, take-up means, a conveyer flight having one end 15 connected to said take-up means, a power shaft, a shaft counter thereto, gear means operable from the counter shaft to operate the take-up means, a gear upon the counter shaft, a transmission shaft mounted for 20 swinging movement about the power shaft as a center and actuated therefrom, a gear upon the power shaft, a gear upon the transmission shaft to mesh with the gear upon the counter shaft, means for swinging the 25 said transmission shaft into and out of position to effect meshing of the last mentioned gears, a bearing for the free end of the transmission shaft, a toggle link connected with the bearing, a toggle link connected with the first mentioned link, man-

ually operable means connected with one of said links for spreading and breaking the toggle, the said manually operable means comprising a rock arm, a rod connected with one of the toggle links, a sleeve connected 35 with the rod and having a slot, the rock arm having a lateral finger projecting through the slot and into the sleeve, and a spring arranged within the sleeve and bearing between one end thereof and the 40 said finger.

9. In a device of the class described, a shaft, sprockets upon the shaft, and a conveyor having side chains passing about the sprockets, the teeth of the sprockets having 45 driving sides presented in one direction of rotation of the sprockets and having their opposite sides rounded to freely sweep past the links of the chains.

10. In a device of the class described, a 50 shaft, means for rotating the shaft, a sprocket on the shaft, a conveyor including chains passing over said sprocket, and guard heads upon the shaft at the outer sides of the sprocket, the heads being of 55 greater diameter than the sprocket and the opposed faces of the heads being convex.

In testimony whereof I affix my signature.

FRANK J. BOBSEINE. [L.S.]
